UNITED STATES PATENT OFFICE

MAXWELL G. GREGG, OF BALLSTON SPA, NEW YORK, ASSIGNOR, BY MESNE ASSIGNMENTS, TO THE FLINTKOTE CORPORATION, OF BOSTON, MASSACHUSETTS, A CORPORATION OF MASSACHUSETTS

PROCESS OF MAKING EMULSIONS

Original application filed June 18, 1922, Serial No. 569,467. Divided and this application filed July 19, 1930. Serial No. 469,087.

This application is a division of my former application, Serial No. 569,467, filed June 19, 1922.

This invention relates to improvements in a process for making emulsions, and refers more particularly to a process particularly adapted to making emulsions of heavy hydro-carbon oils or asphalts by combining same with water and a suitable emulsifying agent.

10 Among the salient objects of the invention are to provide a process whereby emulsions may be formed continuously of two or more materials either under substantial pressure or at atmospheric pressure; to provide a process which under pressure, increases the boiling point of heavy viscous materials and raises the temperatures used without evaporation; to provide a process which is so constructed that it is economical and at the same time is capable of a maximum efficiency; to provide a process in which emulsions can be made continuously, and in which the materials used in making the emulsion are continuously circulated and mixed, at the same time being subjected to heat and pressure.

25 In the drawings, Fig. 1 is a side elevational view of apparatus in which the process may be carried out.

Fig. 2 is a plan view of the same.

30 Referring in detail to the drawings, the conduit 1, preferably of common wrought iron pipe so arranged as to form a continuous circulating tube is provided with shafts 2 and 3. Mounted upon these shafts are propellers 4 and 5, and where the shafts extend outside of the conduit, they are provided with stuffing boxes 6. The shafts are provided with pulleys 7 or connected with any known means for rotating same. The numeral 8 represents a cover or manhole plate which can be removed to permit the circulating tube to be charged. 9 and 10 represent inlets to the conduit and 11 represents an outlet. It may be noted here that more inlets or outlets 45 may be employed if necessary. 12 represents a relief cushion for steam or vapors generated inside the conduit, said cushion being provided with pressure gauge 13 and valve 14, which is preferably a loaded or automatic valve, which latter is used to regulate the

pressure inside the system. Outlet 11 is provided with a valve 15 and inlets 9 and 10 are provided with valves 16 and 17. The conduit may be provided with external heating apparatus or burners 18 for the purpose of heating the material inside the conduit. The entire apparatus may be mounted on the standards or uprights 19.

55 One method of operation of the apparatus may be as follows: The conduit 1, through the cover 8, is charged with a heavy viscous mixture of colloidal clay, as an emulsifying agent, and water. The shafts 2 and 3 are set in motion so that the propellers 4 and 5 are working in a direction to produce a circulation of said material around the conduit 1. The material to be mixed may be brought to the desired temperature by the application of heat as shown in the drawings. When the clay and water mixture is of the proper consistency, inlet valve 16 on inlet 9, which in this instance, is used for the inlet of asphalt, is opened, and this asphalt, having been pre-heated so that it will flow freely, is admitted into the conduit 1 and immediately mixed 60 with the material in the conduit. When the desired temperature and pressure is reached, valve 15 on the outlet 11 is opened to allow 65 the same amount of material to pass out as is being fed to the apparatus through the inlet 9. When the proper percentage of asphalt is mixed with the original charge of the conduit 1, which may be anywhere from 99% down, the inlet valve 17 is opened to allow a continuous flow of the emulsifying agent, which is, in this instance, colloidal clay mixed with water, and the outlet valve 15 opened that much more.

70 As the materials enter through the inlet valves, they are immediately taken up by the circulation through the conduit and formed into a permanent emulsion and the finished emulsion is drawn from the outlet 11.

75 As a feature of my invention, it will be noted that the process may be operated under any pressure desired, thereby permitting the use of high melting point asphalts having a boiling point of 250 to 400° F., or more, in that the proper amount of pressure being exerted naturally increases the boiling point 80 100

of the contents of the mixer so that a temperature in excess of the boiling points of the materials at atmospheric pressure, may be used without evaporation or distillation of said materials. This will produce the proper viscosity for mixing.

It is to be understood that this process is not limited to the use of any one emulsifying agent such as colloidal clay, but may be 10 used for emulsions of heavy vegetable compounds, resins, rubber, or high melting point materials other than asphalts.

I claim as my invention:

15 1. A process of making emulsions, which comprises subjecting a base material, water and an emulsifying agent to agitation to disperse the base material in the water, imparting a cyclic circulation in a horizontal direction to said dispersion, maintaining said 20 cyclic circulation of said dispersion while introducing fresh quantities of base material, water and emulsifying agent to the circulating mass to be dispersed, and withdrawing predetermined amounts of dispersion from 25 said circulating mass.

2. A process of making emulsions, which comprises subjecting a base material, water and an emulsifying agent to agitation to disperse the base material in the water, imparting a cyclic circulation in a horizontal direction to said dispersion, maintaining said cyclic circulation of said dispersion while introducing in separated streams, fresh quantities of base material, water and emulsifying 35 agent to the circulating mass to be dispersed, and withdrawing predetermined amounts of dispersion from said circulating mass.

3. A process of making emulsions which 40 comprises subjecting a base material, water and an emulsifying agent to agitation to disperse the base material in the water, imparting a cyclic circulation in a horizontal direction to said dispersion, maintaining said cyclic circulation of said dispersion while introducing in separated streams, fresh quantities of base material, water and emulsifying agent to the circulating mass to be dispersed, and withdrawing predetermined amounts of dispersion from 45 said circulating mass at a rate and in a quantity corresponding to the rate and quantity of fresh materials being fed to said circulating mass.

4. A process of dispersing a base material 55 in water, which comprises subjecting a base material, water and an emulsifying agent to a forced cyclic circulation in a horizontal direction in a closed ring, subjecting said circulating mass during a portion of the cyclic 60 travel thereof to the action of an emulsifying instrumentality to disperse the base material in the water and form an aqueous dispersion thereof, maintaining said cyclic circulation while introducing fresh quantities of base 65 material, water and emulsifying agent to the circulating mass to be dispersed, and with-

drawing predetermined amounts of dispersion from said circulating mass substantially at a rate and in a quantity corresponding to the rate and quantity of fresh materials being fed to the circulating mass.

In testimony whereof I affix my signature.
MAXWELL G. GREGG.
